GAS MASK CARRIER

Lewis M. McBride, Denver, Colo., and Randolph
Monro, Edgewood, Md.

Application November 15, 1929, Serial No. 407,444

18 Claims. (Cl. 220—29)

(Granted under the act of March 3, 1883, as
amended April 30, 1928; 370 O. G. 757)

This invention described herein may be manufactured and used by or for the Government for governmental purposes, without the payment to us of any royalty thereon.

This invention relates in general to receptacle closures and more particularly has reference to a removable seal for a gas mask carrier.

It is customary after the assembly of gas mask units not intended for immediate use to pack the same in an airtight container charged with an inert gas to prevent deterioration of the rubber and fabric. Previous to this time difficulty has been experienced in obtaining an effective seal for containers of this character which may be readily removed when it is desired to employ the mask packed therein.

An object of this invention is to provide a gas mask carrier having a hermetic seal which may be quickly opened for removal of the mask.

Another object of this invention is to provide a gas mask carrier having a hermetic seal protected against mechanical injury.

Still another object of this invention is to provide a gas mask carrier having a hermetic seal protected against rupture by pressure resulting from expansion or contraction of the fluid contained in the carrier by reason of temperature changes.

A further object of this invention is to provide a gas mask carrier having a metal cover affording a hermetic seal.

A still further object of this invention is to provide a gas mask carrier having a closure equipped with a device for insuring ready removal of the closure irrespective of the ordinary inequalities of solder application at the time of assembling the carrier.

With these and other objects in view which may be incident to our improvements, the invention consists in the parts and combinations to be hereinafter set forth and claimed, with the understanding that the several necessary elements comprising our invention, may be varied in construction, proportions and arrangement, without departing from the spirit and scope of the appended claims.

In order to make the invention more clearly understood, we have shown in the accompanying drawings means for carrying the same into practical effect without limiting the improvements in their useful applications to the particular constructions, which for the purpose of explanation, have been made the subject of illustration.

In the drawings forming a part of this specification Figure 1 is a perspective view of the gas

mask carrier forming the subject matter of this application shown with a preferred form of opening device mounted thereon.

Figure 2 is a perspective view of the carrier shown in Figure 1 having a portion of the closure broken away showing the assembly in section. 60

Figure 3 is a perspective view of the gas mask carrier showing another form of opening device.

Figure 4 is a side view of the carrier shown in Figure 3 having a portion of the closure broken away shown in section. 65

Figure 5 is a perspective view of a gas mask carrier showing still another form of opening device mounted thereon.

Figure 6 is a side view of the carrier shown in Figure 5 having a portion of the closure broken away shown in section. 70

Figure 7 is an enlarged section of the arrangement of the covers and levers of Figures 1 and 2.

Referring more particularly by numerals to the drawings in which the same and similar elements are designated by like symbols of reference throughout and more especially to Figure 2, there is shown a receptacle 1 adapted for use as a gas mask carrier, having a conventional bottom closure 2 crimped over the bottom rim and soldered as necessary to insure a hermetic seal. 75

The receptacle 1 is ribbed as at 3 to add to the rigidity of the structure thereof and is formed with an inwardly projecting bead 4 near the top edge. An inner cover 5 having a downwardly projecting flange 6 formed integral therewith is adapted to be fitted in the interior of the receptacle flush with the rim thereof and the bottom of the flange 6 seated on the bead 4. 80

The upper edge of the ring 9 projects above the rim of the carrier to act as a guard for the shim metal seal 7, the flange on which, is soldered to the inner face of the ring. Ring 9 is turned inwardly at its lower edge to form the flange 11. 85

A top cover 12 having a downwardly projecting flange 13 fitted over the top edge of the ring 9, is secured to the carrier on one side by a flexible hinge 14. It will be particularly noted that the outer cover 12 rests on the top of the ring 9, projecting above the rim of the carrier so that a space 15 is left between the shim metal seal 7 and the outer cover, which is adapted to allow for swelling of the inner cover and seal in the event of expansion of the fluid contained in the carrier. 100

In the preferred form of opening device as shown in Figures 1 and 2, a bolt 16 projects through the inner cover 5 and intermediate seal 105

110

cover 7 to which it is soldered to insure an airtight joint, and outer cover 12 where it is adapted to retain a lug 17 positioned on the top cover opposite the flexible hinge 14, and held by a nut 18.

A plurality of toggle links 19 and 21 are pivoted on the lug through a pin 23 and the opposite ends thereof pivoted to a lever 23 through a pin 24. The top of the lever 23 is bent inwardly as at 25 and a pin 26 projecting laterally on both sides thereof fixedly mounted therein. A plurality of hooks 27 are riveted to the face of the carrier on each side of the lever 23, adapted to receive the pin 26.

The lower end of the lever 23 is formed with a transverse handle 29 having an aperture therein through which is threaded a wire 31 also passed through an eyelet 32 soldered to the body 1 of the carrier, and the ends of the wire held in a lead car seal 33. It will be apparent that any other manner of retaining the lever 23 in position when it is not desired to remove the closure may be employed in place of the arrangement described.

When use of the mask contained in the carrier is required, the lever 23 is raised, pulling the wire 31 through the closed perforations in the car seal and releasing the handle for a more secure grasp. The lever 23 is then rotated about the pin 26 resting in the hooks 27 and continued movement of the handle raises the lug 17 by upward movement of toggle links 19-21. This in turn pulls inner cover 5 upward due to bolt 16, and since seal cover 7 is of frangible material, causes the inner cover 5 to be drawn through the intermediate seal cover 7, and the three covers completely and simultaneously removed.

In Figures 3 and 4 there is depicted a modified form of opening device shown mounted on a container similar to that illustrated in Figures 1 and 2. In this form of closure, however, the ring 9 extends below the indentation formed by the bead 4 on the carrier, and the inturned flange 11 is provided with an extension 34 soldered to the body of the container below the indentation. Also the flange 6 and a portion of the cover 5 is cut away adjacent the opening device as shown at 35.

A cutting blade 36 is mounted on a leaf spring 37 or other flexible support attached to the under side of the bottom cover 5 adjacent the cut-away portion so that the blade is allowed to contact with the intermediate seal cover 7. A wire 38 connected to the support 37 carrying the blade is passed through the intermediate cover 7 and the outer cover 12, the same being soldered to the intermediate cover as at 39 to insure an airtight joint.

The lower end of the wire is tied in an eyelet 41 having a transverse handle 42 formed integral therewith. In this construction the wire 31 is passed over the handle and through the eyelet 32, the ends being in the lead car seal 33 in the same manner as that already described with reference to Figure 1.

When it is desired to remove this type of closure the handle 42 is pulled upward causing the wire to pull through the perforations in the lead seal, whereupon the blade 36 may be drawn upward through the intermediate seal cover by pulling on the wire and loosening the soldered joint 39. After the seal has been broken by cutting with the blade, the covers may be completely and simultaneously removed in the same manner as

has been previously described with regard to the preferred embodiment of this invention.

Still another form of closure and opening device is shown in Figures 5 and 6. In this form of closure the inner cover and intermediate seal, as well as the ring 9, are dispensed with and the flanges 13 of the top cover 12 fitted directly over the rim of the carrier. The cover 12 is secured in position by strips 43 which may be made of shim metal. These strips are bent to form a hook cross section through which is passed a hemmed wire 44 secured at its inner end to the cover 12 and the opposite end passed out. The bent over portion of the strip 43 is soldered to the flange 13 of the cover and the lower edge soldered to the body of the carrier.

A ring 45 having the rim flush with the rim of the carrier is provided with an inward extension 46 having a downwardly projected flange 47 formed thereon soldered to the body of the container, adapted to act as a guard to protect the seal 43.

The free end of the wire 44 extending through a notch 48 in the ring provided for the outlet thereof, is tied through the eyelet 41 in the same manner as the wire 38 described in Figure 3. In this form of device, opening of the carrier is effected by tearing the seal 43 by grasping the handle 42 and pulling up on the wire 44, the cover 12 being carried away with the wire.

It will be appreciated from the foregoing that the several opening devices illustrated lend to a positive rupture of the seal in any one of the types of closures described with the simultaneous removal of the complete closure assembly. Also that the provision of a cover protected against internal or external injury eliminates the likelihood of corrosion existing in rubber or composition seals when exposed to air or other deteriorating influences over long periods.

There is accomplished by this invention a carrier for gas masks having a metal hermetic seal protected against external mechanical injury and internal pressure resulting from expansion or contraction of the fluid contained in the carrier due to temperature changes, which may be quickly opened and functioning of the device insured irrespective of ordinary inequalities of solder application during assembly of the carrier.

While we have shown and described the preferred embodiment of our invention, we wish it to be understood that we do not confine ourselves to the precise details of construction herein set forth, by way of illustration, as it is apparent that many changes and variations may be made therein, by those skilled in the art, without departing from the spirit of the invention, or exceeding the scope of the appended claims.

We claim:

1. A receptacle having an internal bead formed below the rim embodying a closure comprising an inner cover fitted flush with the rim of the receptacle, having a downwardly projecting rim adapted to rest on the bead, a seal cover having edges 140 extending over the rim of the receptacle superimposed on the inner cover, a strip having one edge extending above the rim of the receptacle attached to the side thereof on the other edge, a protective cover fitted on the top strip and secured thereon by a downwardly projecting rim and means to simultaneously remove the covers.

2. A receptacle having a closure comprising an inner cover, a seal cover superimposed on the inner cover, a cutting member flexibly mounted

on the inner cover and means to bring the cutting member in contact with the seal cover.

3. A receptacle having an opening defined by one wall thereof, a closure having a flange telescopically and frictionally engaged with said wall and hermetically sealing said opening, a guard member secured to said receptacle and having a portion surrounding and spaced from said wall defining the opening, sealing means uniting the flange of said closure to said receptacle, and manually operable means for rupturing said sealing means and opening said closure.

4. A receptacle having an opening defined by one wall thereof, a closure for said opening, said closure having an inner cover provided with a flange telescopically engaged with said wall defining the opening, a guard member secured to said receptacle and having a portion surrounding and spaced from said wall defining the opening, an outer cover telescopically engaged with said guard member, means for sealing the inner cover to said receptacle, and manually operable means for rupturing said sealing means and simultaneously removing both covers.

25 5. The invention as defined in claim 4 wherein said outer and inner covers are spaced from one another to allow swelling of the inner cover.

6. A receptacle having one wall thereof defining an opening, an inner cover telescopically engaged with said wall to close the opening, a shim metal cover superposed on said inner cover, means for sealing said shim metal cover to said receptacle, and an outer protecting cover completely enclosing said inner and shim metal covers and secured to said receptacle.

7. A receptacle having an opening defined by one wall thereof, a closure having a flange telescopically engaged with said wall, means hermetically sealing said closure to said receptacle including a thin metal member capable of being readily sheared, a guard member on said receptacle projecting beyond the thin metal member, and manually operable means for rupturing said thin metal member and opening said closure.

45 8. A receptacle having an opening defined by one wall thereof, a cover having a flange in frictional engagement with said wall, means hermetically sealing said opening including a thin

metal member capable of being readily sheared, a guard member on said receptacle and projecting above said thin metal member, and manually operable means for first rupturing said thin metal member and then opening said cover by 80 a continuous movement thereof.

9. A receptacle having a closure comprising a thin metal seal cover, an inner cover supporting said seal cover, an outer cover protecting said seal cover, and means for simultaneously opening 85 said inner and outer covers and rupturing said seal cover.

10. A receptacle having a closure comprising an inner cover, a thin metal seal cover superposed on said inner cover and sealed to said receptacle, and 90 manually operable means to shear said inner cover through said seal cover.

11. A receptacle having an opening defined by one wall thereof, a closure including an inner cover having a flange in frictional engagement 95 with said wall, a guard member secured to the receptacle and projecting above said flange, a seal cover superposed on said inner cover, hermetical sealing means uniting said seal cover to said guard member, and an outer cover telescopically engaging said guard member and spaced above the seal cover.

12. A receptacle having an opening defined by one wall thereof, a closure having a flange telescoped over said wall, a guard member secured 105 to said receptacle surrounding said telescoped flange but spaced therefrom, a thin metal sealing member positioned between said guard and flange, a pull wire encased by said thin metal member and having one portion accessible for pulling the 110 same, and sealing means uniting said thin metal member to said flange and said receptacle.

13. A receptacle having an open end provided with a closure comprising an inner cover supported by the receptacle, a frangible intermediate cover superposed on and supported by said inner cover and sealed to the receptacle, and an outer protecting cover closing the open end of the receptacle and completely shielding the intermediate cover from accidental injury.

LEWIS M. MCBRIDE.
RANDOLPH MONRO.
